Potomac, Md. 20854

Filed Aug. 19, 1966, Ser. No. 3,543

Term of patent 14 years

(Cl. D13—1)

FIG. 2

FIG. 1

FIG. 3

FIG. 4

FIG. 1 is a perspective view of a booth for acoustical devices embodying this invention, with dot and dash lines suggesting the mounting of the booth on a stand or the like; the suggestion shown by the dot and dash lines forming no part of the design of the booth;

FIG. 2 is a top elevation thereof;

FIG. 3 is a front elevation of the booth; and

FIG. 4 is a side elevation thereof.

The dot and dash lines shown in FIG. 1 are not shown in FIG. 3 or 4 because they form no part of the design of the booth and for convenience of illustration.

I claim:

The ornamental design for a booth for acoustical devices, as shown and described.
